UNITED STATES PATENT OFFICE

WILLIAM HUGH MILLS, OF ATTLEBORO, MASSACHUSETTS

LIFE SAVING AND SALVAGE APPARATUS FOR USE WITH SUBMARINES

Application filed March 2, 1929. Serial No. 343,888.

This invention relates to life saving and salvage apparatus for use with submarines.

An important object of the invention is to provide an apparatus of this character permitting access to the interior of a sunken submarine, provided a chamber of the submarine is water-tight without the necessity of subjecting this chamber to the pressure of the surrounding water.

10 A further and more specific object of the invention is to provide a construction permitting the attachment to a submarine of an escape hatch leading from the submarine to the surface of the water.

15 A still further object of the invention is to provide means for indicating the position of a sunken submarine.

These and other objects I attain by the construction shown in the accompanying 20 drawings, wherein for the purpose of illustration is shown a preferred embodiment of my invention and wherein:—

Figure 1 is a view showing life saving and salvage apparatus constructed in accordance 25 with my invention in use;

Figure 2 is a front elevation of the supports carried by the salvage vessel;

Figure 3 is a sectional view showing the 30 connections of the salvage apparatus to the submarine;

Figure 4 is a detail view partially in section of the signalling means;

Figure 5 is an end elevation of the signalling means.

35 Referring now more particularly to the drawings, the numeral 10 generally designates a plate attached to the deck of a submarine having threaded or otherwise secured therein a hatch 11 which is surrounded by a tubular boss. The hatch 11 is removable from the interior of the submarine and its removal establishes communication between the interior and exterior of the submarine. The numeral 12 generally designates a tube of a length to extend from the plate 10 to a point above the surface of the water. This tube in its lower end has a removable hatch 13 which is removable through this lower end and upon its lower

40 end has a rotatable coupling 14 adapted to engage and bring the tube into sealing engagement with an exteriorly threaded annular boss 15 surrounding the hatch 11 of the plate.

45 The upper end of this tube is adapted to be extended through a guide ring 16 carried by and extending outwardly from the deck of a salvage vessel and this upper end is equipped with a ring 17 provided with an eye or eyes 18 for engagement with hoisting tackle 19. The hoisting tackle 19 is connected through pulleys 20 and 21 mounted respectively upon a mast 22 and a yard 23 extending outwardly from this mast to a counterweight 24 vertically slidably upon the mast and adapted to counterbalance to the greatest possible extent the tube 12. The yard 23 may be conveniently employed to support the sheave 25 of a hoisting line 26, one run of which is directed into the upper end of the tube and which may serve as means for elevating persons or objects from the interior of the submarine.

50 In the use of the apparatus just described, the tube is lowered into position and is coupled to the plate by a diver. The occupants of the submarine then remove the hatches 11 and 13 and thus place the interior of the submarine in communication with the atmosphere through the tube 12. This tube 55 will be made of sufficient size to permit escape of the occupants of the submarine therethrough. While the plate 10 is at present illustrated as being located upon the upper surface of the deck of the submarine 60 and the submarine is shown as provided with but a single plate, it will be obvious that a number of these plates might be employed and they might be located at different points, so that the life saving and salvage apparatus can be employed if the submarine is canted. The plate furthermore 65 preferably provides a means for introducing air to the interior of the submarine, having a valve-controlled port 27 surrounded by a threaded boss 28 to which an air hose 29 may be connected.

70 One of the plates of the submarine will be equipped with a position indicating buoy mechanism, such as more particularly shown 75

75

80

85

90

100

in Figure 4. This buoy mechanism comprises a reel 30 having a cable line 31 attached thereto and wound thereon. The free end of this cable line is attached to a 5 buoy 32 which may be suitably lettered to indicate its purpose. The buoy, during normal submergence of the submarine, is held against escape from the submarine by means of a hook 33. This hook is pivoted to an 10 end frame member 34 of the drum mounting and would normally swing upwardly to permit escape of the buoy therefrom during submergence. It is, however, held against such upward movement by means of a 15 shackle yoke 34 which engages its outer end and holds it against vertical movement. This shackle yoke has an operating rod 35 secured thereto which extends through the deck and beneath the deck is equipped with 20 an operating handle and an adjustable stop element 37 for restraining upward movement of the rod. This rod at this point of passage through the deck is sealed thereto in any suitable manner. In the present instance, a rubber tube 38 is shown as sealed 25 to the rod at its upper end and to the deck at its lower end, this tube being in surrounding relation to the rod.

It will be obvious that by employing apparatus of this character, salvage operations 30 in connection with submarines may be greatly facilitated and the likelihood of loss of life in event of sinking of a submarine to a large extent eliminated.

35 It will also be obvious that the construction hereinbefore set forth is capable of a certain range of change and modification without materially departing from the spirit of the invention and I accordingly do not 40 limit myself thereto except as hereinafter claimed.

I claim:—

45 1. Means for indicating the position of a sunken vessel comprising a float, a reel, means for rotatably mounting the reel on the vessel, a flexible member wound about said reel, a V-shaped member secured to said float and removably seating on said mounting means for said reel, means for connecting one side of said V-shaped member to the flexible means, a ring loosely mounted in the opposite side of said V-shaped member, a pivoted arm secured to said mounting means, said arm having an upturned end 50 portion, said arm being adapted to extend through said ring whereby to releasably hold said float on said mounting means, and a vertical movable member engaging the upturned end portion of said arm whereby to normally hold said arm in outstanding position, said movable vertical member extending inwardly of the vessel whereby to permit operation thereof remotely from the 55 float.

60 2. Means for indicating the position of a

sunken vessel comprising a float, a winding reel, supporting means mounted on the vessel for the reel, a V-shaped member secured to the float and normally seating on said supporting means, a flexible member wound on said reel, means connecting one end of said flexible member to one leg of said V-shaped member, a ring dependently mounted in the other leg of the V-shaped member, a pivoted locking member mounted on said support and engaging said ring, and manually operable means engaging said locking means, said manually operable means upon vertical movement thereof, being adapted to release said locking means whereby to permit said float to rise upwardly.

In testimony whereof I hereunto affix my signature.

WILLIAM HUGH MILLS.
